UNITED STATES PATENT OFFICE.

LORENZO B. HORNER, OF HAMMOND, INDIANA.

DOOR HANGER.

1,402,612.

Specification of Letters Patent.

Patented Jan. 3, 1922.

Application filed July 9, 1921. Serial No. 483,583.

To all whom it may concern:

Be it known that I, LORENZO B. HORNER, a citizen of the United States, residing at Hammond, in the county of Lake and State 5 of Indiana, have invented new and useful Improvements in Door Hangers, of which the following is a specification.

This invention relates to door hangers and has for its object the provision of a 10 novel door hanger designed for use on the doors of garages, ware houses, factories and the like, the hanger being designed particularly for use in connection with inclined trackways from which doors are suspended 15 in such a way that they will close automatically upon the burning of a cable carrying a counterbalancing weight.

An important object is the provision of a 20 hanger of this character which includes a rigid frame secured to the door and within 25 which is pivoted a movable frame carrying the track engaging rollers, the arrangement being such that the movable frame will accommodate itself to an inclined track while the stationary frame will extend vertically 30 from the door.

Another object is the provision of a 35 hanger of this character which is provided with efficient lubricating means which will insure easy running of the rollers at all 40 times and at the same time prevent rusting thereof.

A further object is the provision of a device of this character in which the parts are 45 so arranged and mounted that the broken wheel may be easily replaced without necessitating discarding the entire hanger.

An additional object is the provision of a 50 device of this character which will be simple and inexpensive in manufacture, highly efficient in use, durable in service, and a general improvement in the art.

With the above and other objects and advantages in view, the invention consists in 55 the details of construction to be hereinafter more fully described and claimed and illustrated in the accompanying drawings in which—

Figure 1 is an elevation of a door associated with an inclined track and showing 60 my hangers in position,

Figure 2 is a front elevation of one of 65 my hangers on a larger scale,

Figure 3 is an elevation of the opposite 70 side,

Figure 4 is an edge view,

Figure 5 is a horizontal sectional view taken through the journals of the rollers,

Figure 6 is a horizontal sectional view 60 through a modified form, and

Figure 7 is an elevation of still another modified form.

Referring more particularly to the drawings, the letter A designates a portion of a 65 wall having a door opening B therein above which is mounted a track C which is inclined. It should be understood that the track C need not be inclined but in many instances, especially on factory doors, an 70 inclined track is used and the door has connected therewith a cable or rope passing over a suitable guide pulley and carrying a counter-balancing weight which normally holds the door open. The purpose of such an arrangement is that in face of fire the 75 rope will burn through and permit the door to close gravitationally so as to cut off communication between a burning building or room and the adjacent room to prevent the spread of fire. The letter D designates the 80 door which may be of any ordinary or preferred construction and which does not itself form any part of the present invention.

In carrying out my invention I provide a 85 door hanging means comprising a plurality of hangers which are similar and each of which includes an inverted U-shaped rigid frame 10 having one leg 11 longer than the other and bolted or otherwise secured upon the door D. Extending transversely across 90 the frame 10 is a hollow shaft 12 which is rigid and which is prevented from longitudinal displacement by any suitable means. Rotatable upon this shaft is a 95 grooved roller 13 at the opposite sides of which are disposed washers 14. The hollow shaft is formed with a hole 15 within the confines of the bearing portion of the roller.

The movable frame comprises a pair of 100 bars 16 which are disposed on opposite sides of the roller or rather upon opposite sides of the washer 14 outwardly of the roller, these bars being formed with holes for the passage of the shaft 12 whereby the bars will be capable of rocking movement upon 105 the shaft. Connected with one projecting end of the shaft 12 is a T 17 with the opposite ends of which are connected pipes 18 which are bent into substantially L-shape 110 and which pass through holes in the end portions of the bars 16 and which have their extremities threaded for engagement there-

on of nuts 19. The ends of these pipes should be plugged by any suitable means indicated at 20. Rotatable upon the pipes 18 between the bars 16 are rollers 21 against opposite sides of which are disposed washers 22. The pipes 18 are provided with holes 23 within the hub portions of the rollers 21. Connected with the top of the **T** 17 is a grease cup 24 of ordinary construction by means of which grease may be fed to the hollow shaft 12 and to the pipes 18, the grease issuing from the holes 15 and 23 for effecting lubrication of the rollers at their points of contact with the shaft 12 and the pipes 18. Secured within the bight portion of the stationary frame 10 is an elongated sheet metal shield 25 which is for the purpose of protecting the rollers against the weather.

20 In the use of the hangers it will be seen that the rigid frames 10 extend vertically from the door D while the movable frame formed by the bars 16, may pivot upon the hollow shaft 12 so that the door will hang vertically even from an inclined track. The rollers 13 and 21 of course travel upon the track in the usual manner and they will be thoroughly lubricated and prevented from rusting owing to the provision of the grease cup and the lubricant conducting pipe which serve the additional purpose of bearing supports for the outer rollers.

25

30

In the form of the device shown in Figure 6, I have omitted the central roller and the central shaft 26 may be solid instead of hollow, its only function in this case being to pivotally support the movable frame. In this instance it is also unnecessary to use a **T** as in the previously described form as an ordinary coupling 27 will suffice. In other respects this form is identically the same as the first described form and its operation is the same.

40 In Figure 7 I have shown merely a rigid frame of the same shape as the frame 10 and having a hollow shaft 28 journaled therethrough and supporting a single roller 29. This shaft carries a grease cup 30 for effecting lubrication, the shaft being provided within the hub of the roller with a hole, as in the first described form.

45 From the foregoing description and a study of the drawings it will be apparent that I have thus provided a simply constructed and consequently inexpensive door hanger which will accommodate itself to

tracks of various angular inclination, which will operate smoothly and consequently give good service, which will be self lubricating and in which the construction is such that a broken roller may be replaced without necessitating replacing the entire hanger.

50 While I have shown and described the preferred embodiment of my invention, it is of course to be understood that I reserve the right to make such changes in the form, construction, and arrangement of parts as will not depart from the spirit of the invention or the scope of the subjoined claims.

Having thus described my invention, I claim:

1. A door hanger comprising an inverted **U**-shaped rigid frame, a shaft journaled transversely of said frame, a movable frame including spaced bars rockably mounted upon said shaft, a pair of pipes substantially **L**-shaped extending through the end portions of said bars, rollers journaled upon said pipes between said bars, said pipes being provided with holes at the hub portions of said rollers, and means for supplying grease to said pipes. 75

2. A door hanger comprising an inverted **U**-shaped rigid frame, a shaft journaled transversely of said frame, a movable frame including spaced bars rockably mounted upon said shaft, a pair of pipes substantially **L**-shaped extending through the end portions of said bars, rollers journaled upon said pipes between said bars, said pipes being provided with holes at the hub portions of said rollers, and means for supplying grease to said pipes, said means comprising a coupling connecting said pipes, and a grease cup mounted upon said coupling. 90

3. A door hanger comprising a rigid frame of inverted **U**-shape, a hollow shaft extending transversely thereof, a roller journaled on said shaft, said shaft being provided at the hub portion of said roller with a hole, a **T** connected with one end of said shaft and carrying a grease cup, a pair of bars rockable upon said shaft at opposite sides of said roller, **L**-shaped pipes connected with said **T** and extending through the end portions of said bars, and rollers journaled on said pipes between said bars, said pipes being formed with holes within the hub portions of said last named rollers. 95

40 In testimony whereof I affix my signature. 110

LORENZO B. HORNER.
